Inventor
Merle B. McCune

J. Reaugh Keller, Attorney

UNITED STATES PATENT OFFICE.

MERLE B. McCUNE, OF WOODLAWN, PENNSYLVANIA.

NOZZLE.

Application filed July 2, 1921. Serial No. 482,155.

To all whom it may concern:

Be it known that I, MERLE B. McCUNE, citizen of the United States, residing at Woodlawn, in the county of Beaver and 5 State of Pennsylvania, have invented certain new and useful Improvements in Nozzles, of which the following is a specification.

The present invention relates to improvements in nozzles such as are used on hose used at gasoline or other filling stations.

The main object of my invention is to provide a nozzle provided with simple and compact means whereby it may be quickly 15 and easily attached to the gasoline tank of an automobile or to any other tank or compartment adapted to receive a liquid, so as to obviate the necessity of employing someone to hold the nozzle in place when the 20 tank or other compartment is being filled.

Another object of the invention is to provide a nozzle with adjustable means which, when the end of the nozzle is inserted in the filling opening of a tank or other compartment, may be so adjusted as to prevent the 25 accidental withdrawal of the nozzle while the tank or other compartment is being filled.

Still another object of the invention is to 30 provide improved means as above described which can be used in connection with a nozzle of conventional form and wherein the construction of the nozzle need not be changed to any appreciable extent to accommodate the same.

A further object of the invention is to 35 provide a nozzle equipped with means as above set forth which is simple in construction, cheap to manufacture and wherein the 40 moving parts are so arranged whereby they are not likely to get out of order.

Various other objects and advantages of 45 my invention will become apparent during the continuance of the following description.

In the drawings:—

Figure 1 is a view in side elevation showing my invention as in its preferred embodiment, the improved retaining means being 50 shown in a closed or folded position.

Figure 2 is a view similar to Figure 1 showing the retaining means in an open or extended position.

Figure 3 is a view in side elevation taken 55 at right angles to the views shown in Figures 1 and 2.

Figure 4 is a view in horizontal cross section taken on line 4—4 of Figure 1.

In the drawings I have shown, for purposes of illustration, a nozzle 10 which is 60 provided with screw threads 11 at one end to facilitate its connection at one end with a gasoline hose or other liquid conducting means. The opposite end of the nozzle is 65 adapted to be inserted into a filling opening 12 of a tank or compartment 13 in order to fill the tank or compartment with a liquid, such as for instance gasoline, from a gasoline filling station. Along one side, the 70 nozzle 10 is provided with a series of transverse teeth or other retaining means such as shown at 14 and in its present embodiment, it is contemplated to terminate the teeth 14 flush with the outer surface of the nozzle so that other means, as will be hereinafter described, may slide freely on the 75 body of the nozzle.

With a view to equipping the nozzle with the improved retaining means of my invention, I provide the nozzle with a collar 15 80 from which depend at substantially diametrically opposite points, as at 16, arms 17 which have oppositely extending angular extensions 18 that are slotted as at 19 for the reception of studs 20 arranged at substantially diametrically opposite points near the open or outer end of the nozzle as clearly shown in Figures 1 and 2. It is contemplated to have the studs 20 arranged in alignment with the point of connection 16 90 between the arms 17 and the collar 15 so that when the collar 15 is moved downwardly or outwardly towards the open end of the nozzle, the extensions 18 of the arms 17 will be directed upwardly in the position shown 95 in Figure 2. However when the collar is moved upwardly or inwardly on the nozzle 10, the co-action of the studs 20 and the slots 19 cause the arms 17 and the extensions 18 to assume the position shown in Figure 1. 100

In order to provide means to maintain the collar 15 in certain adjusted positions on the body of the nozzle, I first provide the collar 15, connected as at 21, with a bar 22, that extends longitudinally with respect to 105 the body of the nozzle 10 and which is in turn provided adjacent its ends with longitudinal slots 23. I now provide the body of the nozzle with spaced studs 24 that are aligned with the series of teeth 14 as shown in Figures 1 and 2, the studs entering the slots 23 of the bar 22 and being provided 110

with enlarged heads so as to prevent accidental dislodgment of the bar with respect to the nozzle. This arrangement will limit the sliding movement of collar 15 on the body of the nozzle. I further provide the collar 15 with a leaf spring 25 that lies beneath the bar 22 and which is provided at its free ends with a lug 26 that is adapted to lie between certain of the teeth 14 so as to maintain the collar 15 in a rigid position with respect to the body of the nozzle and at the same time permit free and easy adjustment of the collar. The lug 26 is normally held in a seated position between certain of the teeth 14 by reason of the normal tendency of the spring 25 and is thereby evenly held against accidental dislodgment. However, I equip the leaf spring 25 with a stud 27 that is slidably mounted through the bar 22 and provided adjacent its outer end with a handle or manipulating portion 28 whereby the leaf spring 25 may be moved so as to disengage the lug 26 of the teeth 14 when it is desired to adjust the collar 15 on the body of the nozzle.

When it is desired to fill a tank or other compartment the open end of the nozzle is first inserted in the filling opening of the tank or compartment, such as shown in Figure 2, the parts being normally in the position shown in Figure 1. The operator then grasps the handle or manipulating portion 28 and applies an outward stress so as to disengage the lug 26 from the teeth 14 whereby the collar may be moved towards the outer end of the nozzle such as will cause the extensions 18 of the arms 17 to assume the extended position as shown in Figure 2.

When the handle or manipulating portion 28 is released, the lug 26 will again seat between certain of the teeth 14 whereby the collar 15 will be firmly held against accidental movement. When the extensions 18 of the arms 17 are in the position shown in Figure 2, it will be observed that accidental

withdrawal of the nozzle from the tank or other compartment that is being filled will be prevented.

From the foregoing it is believed that the advantages and novel features of my invention will be readily understood and therefore further detailed description is deemed unnecessary.

What is claimed is:

1. The combination with a nozzle of a collar adjustably mounted thereon, arms carried by said nozzle and being pivoted with respect thereto, angular extensions formed on the free ends of said arms said extensions extending in opposite directions and being provided with longitudinal slots, studs fixed to said nozzle and projecting through said slots whereby upon longitudinal adjustment of said collar said arms will be rocked upon their pivots to extend or fold said angular extensions with respect to the adjacent end of said nozzle substantially as described. 55

2. The combination with a nozzle provided with a series of teeth, of a collar slidably mounted on said nozzle, means carried by said collar and engageable with teeth to maintain said collar in certain adjusted positions on said nozzle, means to withdraw said last mentioned means from engagement with said teeth whereby the collar may be adjusted, arms pivotally mounted on said collar, angular extensions formed on the free end of said arms extending in opposite directions, said angular extensions being provided with longitudinal slots, and studs carried by said nozzle adjacent one end thereof and entering said slots whereby upon longitudinal adjustment of said collar on said nozzle, said angular extensions will be extended or folded with respect to said nozzle substantially as and for the purpose specified. 75 80

In testimony whereof I affix my signature.

MERLE B. McCUNE.
